UNITED STATES PATENT OFFICE.

HENRY S. DAVIS, OF SEYMOUR, IOWA, ASSIGNOR OF ONE-HALF TO JAMES T. PHILLIPS, OF SAME PLACE.

CURTAIN-FIXTURE.

SPECIFICATION forming part of Letters Patent No. 633,815, dated September 26, 1899.

Application filed April 15, 1897. Serial No. 632,284. (No model.)

To all whom it may concern:

Be it known that I, HENRY S. DAVIS, a citizen of the United States, residing at Seymour, in the county of Wayne and State of Iowa, have 5 invented certain new and useful Improvements in Curtain-Fixtures; and I do hereby declare the following to be a full, clear, and exact description of the invention, such as will enable others skilled in the art to which it appertains to make and use the same.

This invention relates to improvements in fixtures for curtain-shade rollers, the object of the same being to provide devices for this purpose which will possess the special advantages of being cheap in construction, effective 15 in their application, and susceptible of presenting an ornamental appearance if plated with silver or nickel.

The invention contemplates a particular 20 construction of the brackets which are employed in supporting the shade-roller and curtain-pole.

Having the above object in view, the invention consists in making the fixtures of wire, 25 the wire forming the brackets being given certain peculiar bends to provide the rests or bearings for the roller and pole and other bends which allow of a degree of elasticity to the inclined support or brace, all as will be 30 hereinafter fully set forth, and specifically recited in the claim, reference being had to the accompanying drawings and to numerals which designate the different parts.

In the drawings forming part of this specification, Figure 1 is a perspective view showing the application of my improved fixtures. Fig. 2 is a detail view of one of the brackets which support the shade-roller and pole.

As hereinbefore mentioned, the fixtures 40 which are constructed in accordance with my invention are made of wire of the proper gage which will bend freely and at the same time possess sufficient strength for the purposes to which the fixtures are adapted. In forming 45 the brackets which support the shade-rollers a piece of wire of suitable length is used and its end bent to form eyes 1 1 at right angles with the body of the wire. Adjoining one of these eyes the wire is bent or looped to prevent the recess or bearing 2, the outer mem-

ber of the loop being extended upward beyond the end portion adjoining the eye, and is then bent into a curve 3 of the proper arc, the outer end of said curve or arc being above the plane of its inner end, and from said arc 55 the wire is bent into a peculiar shape to form the support or brace which terminates in the other eye at the opposite end of the wire. In forming this brace the wire is curved outward from the arc 3 and is formed into a number 60 of separate coils 4, which extend alternately in opposite directions and practically form springs, as well as present an ornamental brace. By this manner of bending the wire which forms the brackets the eyes 1 1 will be 65 on a vertical line with each other and present the holes through which the retaining-screws pass and the bends 2 and 3 present proper bearings for both the shade-roller and curtain-pole, the latter resting within the 70 curve or arc 3, while the projecting pins of the former rest within the loop 2, which adjoins the arc, but is on a lower plane. The part of the wire which forms the brace for the horizontal portion presenting the bearings is 75 bent into the coils disposed as shown and hereinbefore described in order that any undue tension or pull upon either the shade-roller or curtain-pole will allow the brackets 80 to give, and thereby save the curtains or tend to prevent accident to the same.

A clamp or holder for the draw-cord of a curtain-shade is illustrated in Fig. 1, conveniently formed of a piece of wire bent upon itself to present eyes 5 5 and terminals 6 6, 85 which serve as a cleat or hook for the draw-cord.

From the foregoing description in connection with the accompanying drawings it will be apparent that I provide curtain-fixtures 90 which can be cheaply constructed and at the same time possess the desired strength with other qualifications required in this line.

Having thus described my invention, what I claim as new, and desire to secure by Letters 95 Patent, is—

A curtain fixture or bracket made up of a single piece of wire, the ends of which are bent into eyes and stand in planes at right angles to the adjacent parts of the bracket, 100

the wire being depressed or looped adjoining the uppermost eye and extending upward from said loop and bent into an arc of a circle, the outer end of which is above the plane 5 of the inner end, and from which the said wire is further bent in separate coils which form an inclined resilient and ornamental brace that terminates in the eye at the lower part of the bracket, the said separate coils

being alternately extended on opposite sides 10 of the said brace, substantially as described.

In testimony whereof I have signed this specification in the presence of two subscribing witnesses.

HENRY S. DAVIS.
